UNITED STATES PATENT OFFICE.

JOHN H. A. BOUSFIELD, OF ST. JOHNSBURY, VERMONT, ASSIGNOR TO E. & T. FAIRBANES & COMPANY, OF ST. JOHNSBURY, VERMONT, A CORPORATION OF VERMONT.

SCALE.

1,128,844.

Specification of Letters Patent. Patented Feb. 16, 1915.

Application filed June 16, 1913. Serial No. 773,960

To all whom it may concern:

Be it known that I, JOHN H. A. BOUSFIELD, a citizen of the United States of America, residing at St. Johnsbury, in the 5 county of Caledonia and State of Vermont, have invented certain new and useful Improvements in Scales, of which the following is a specification, reference being had therein to the accompanying drawings.

10 The invention relates to scales and more particularly to pit scales such as are employed for railroad tracks or the like.

The invention resides in the novel construction, arrangement and combination of 15 parts as will more fully hereinafter appear and as claimed.

In the drawings,—Figure 1 is a cross section through a scale embodying my invention; Fig. 2 is a fragmentary top plan view 20 thereof; Fig. 3 is a side elevation of the parts shown in Fig. 2; Fig. 4 is a side elevation of the fifth lever; Fig. 5 is an end elevation thereof; Fig. 6 is a top plan view illustrating certain details of construction; 25 Fig. 7 is an end elevation looking at the free end of the fifth lever; and Figs. 8 and 9 are sections through the fifth lever; and Fig. 10 is a plan view of the casting.

The scale illustrated in the drawings is 30 of the railroad track type and comprises a plurality of systems of levers as A and B which are connected to the fifth lever C, and to which the load is transmitted; such an arrangement of parts being well known 35 in the art. In this type of scales, that is— where a plurality of systems of levers are employed, since the greater weight of the load shifts from one system to the other, particularly during the moving of the load 40 over the tracks of the scale, there is a tendency for the systems of levers to pull unevenly upon the fifth lever, thereby introducing objectionable vibration. I have therefore, so constructed the connection be-

tween the lever systems as to avoid the objectionable torsional stresses or strains being transmitted to the lever C. Each system of levers is herein shown as composed of levers A² and compound levers D and 50 E. The levers A² extend at right angles to the levers D and E and transmit the load to be weighed to said levers. The levers E have their adjacent ends provided with knife edge pivots F with which saddle-

blocks G engage. Each block is provided 55 with downwardly-extending bolts or rods H I respectively arranged upon opposite sides of its pivot F and having the lower ends passing through apertures J in the head K of a clevis L. The lower end of this clevis 60 is bifurcated to receive the upper end M of a bearing member N, and is connected thereto by means of a bolt O. The member N is provided with spaced loops P which carry bearing blocks Q for engaging a knife 65 edge pivot R on the fifth lever. In order to obtain a proper line contact between the bearing Q and the pivot R when one member E moves independently of the other, a slight lateral rocking is permitted by providing the bottom face of the block Q with a curved surface S which engages the base 70 of the loop P.

The fulcrum for the fifth lever is formed of a heavy casting T having the base U 75 suitably secured to a support V and provided with spaced upwardly-extending sides W. In order to permit the fulcrum bearing to be of the desired width the sides have removable caps X which carry the bearing 80 blocks Y, in the form of loose rocker steels, so as to maintain at all times a full line contact with the knife edge pivot Z on the fifth lever.

A' are bolts passing through the sides and 85 the caps, for securing the latter to the former.

As before stated, the provision of the removable caps permits a wide fulcrum bearing, and as shown in Fig. 4 this fulcrum 90 bearing is wider than the connection to the extension lever E, so that the strains transmitted through the extension lever will come inside of the points of fulcrum of the fifth lever. Such an arrangement also allows 95 of reinforcing the portion of the fifth lever that carries the pivot Z. Thus the latter is provided with a plurality of cross-ties B', forming in effect an I-shaped cross-section. One of these ties is positioned adjacent the pivot Z and has integral, lateral extensions C' that not only permit of spacing the pivot points the desired width, but also serves to materially reinforce the pivots. Similarly the beam C is provided 100 with integral, lateral enlargements D' forming a comparatively wide reinforcement for the pivot R. In order to permit

the bearing N to be engaged with the pivot R, the upper portion M which connects the spaced loops P, is formed in two sections, as shown in Fig. 6, these sections being 5 clamped together after the parts are properly assembled, by means of bolts E'.

The outer end of the fifth lever is connected to the steelyard rod F' by means of a link G' having a rocker bearing H' that 10 engages a knife edge pivot I' carried by a member J' preferably in the form of a sleeve adapted to engage over the free end of the lever C and secured thereto by means of bolts K'.

15 By the arrangement of parts heretofore described the torsional strains transmitted to the lever C not only are reduced to a minimum, but the rocker connections between the bearing blocks Q Y and H' insure a full line contact with their respective pivots at all times. To further lessen the vibration and torsion when the weight is moved over the scale, I tie the fulcrum stands of the main and extension levers so 20 as to form in effect a continuous frame. Thus as shown, L' M' N' O' P' and Q' are the fulcrum stands for the main and extension levers. The stands M' Q' and L' O' are connected by means of longitudinally-extending braces R', preferably of channel configuration, these braces having their ends bolted to brackets S' formed integral with the stands. The extension lever stands L' M' and O' Q' are connected to 25 the stands N' P' of the main levers by means of transversely-extending ties T' having their opposite ends respectively connected to brackets U' V' formed integral with the extension and main lever stands 30 respectively. When the stands are so connected an exceedingly rigid structure is provided.

What I claim as my invention is:—

1. In a scale, the combination with complementary main levers, of a lever adapted to be operated thereby, and connections between said main levers and said operated lever, including a rigid sectional bearing and a fulcrum connection between said bearing and said operated lever.

2. In a scale, the combination with complementary main levers, of a lever adapted to be operated thereby, and connections between said main levers and said operated lever, including spaced loops provided with laterally-extending portions at their upper ends adjustably connected together.

3. In a scale, the combination with complementary main levers, of a lever adapted to be operated thereby, and connections between said main levers and said operated lever, including spaced loops arranged upon opposite sides of said operated lever, bearing blocks carried by said loops, and a 65 knife-edge pivot carried by said operated

lever engaging said blocks, said loops being provided with laterally-extending portions adjacent their upper ends adjustably connected together.

4. In a scale, the combination with a main lever, of a lever adapted to be operated thereby, a connection between said levers, a support provided with spaced portions intermediate which said operated lever is arranged, one of said spaced portions including a detachable cap carrying a knife-edge pivot, and bearing connections between said portions and the operated lever.

5. In a scale, the combination with a main lever, of a lever adapted to be operated thereby, a connection between said levers, a support provided with spaced portions intermediate which said operated lever is arranged, one of said spaced portions including a detachable cap carrying a knife-edge pivot, and bearing connections between said portions and the operated lever, one of said connections having a part thereof carried by said cap.

6. In a scale, the combination with a main lever, of a lever adapted to be operated thereby, a support for said lever comprising spaced portions intermediate which said operated lever is arranged, lateral extensions upon said lever, and pivotal connections between said lateral extensions and said spaced portions, one of said spaced portions including a detachable cap.

7. In a scale, the combination with a main lever, of a lever adapted to be operated thereby, a support for said lever comprising spaced portions intermediate which said operated lever is arranged, lateral extensions upon said operated lever, said spaced portions including a detachable cap, a fulcrum connection intermediate each of said lateral extensions and said spaced portions, including a knife-edge pivot carried by the one and a bearing block carried by the other.

8. In a scale, the combination with a main operating lever, of a lever adapted to be operated thereby, a support for said operated lever including detachable caps, bearing blocks carried by each of said caps and having a rocking connection therewith, and knife-edge pivots projecting laterally from said operated lever and engaging said bearing blocks.

9. In a scale, the combination with a main operating lever, of a lever adapted to be operated thereby, a support comprising spaced bifurcated members, detachable caps connected to said spaced bifurcated members, laterally-extending portions upon said operated lever, and a fulcrum connection between said caps and said lateral extensions.

10. In a scale, the combination with a main lever, of a lever adapted to be operated thereby, a support for the operated lever, comprising spaced members intermedi-

ate which said operated lever is arranged, said spaced members having a bifurcated portion, caps arranged over said bifurcations, securing members for connecting the 5 caps to the bifurcations extending through the latter, and a knife-edge pivot and bearing connection between each of said spaced portions and the operating lever.

11. In a scale, the combination of an operated lever, of a steelyard rod and a connection between said steelyard rod and said operated lever, comprising a section carried by and secured to said lever, a loop operatively connected to the steelyard rod, a bearing block carried by and having a limited 15 rocking movement in relation to said loop, and a knife-edge bearing upon said section engaging said bearing block.

12. In a scale, the combination of an operated lever, of a steelyard rod and a connection between said steelyard rod and said operated lever, comprising a section carried by and secured to said lever, a loop spanning 20 said section, a bearing block carried by and having a limited rocking movement in relation to said loop, and a knife-edge bearing upon said section engaging said bearing block.

13. In a scale, the combination with a plurality of levers, of longitudinally spaced fulcrum stands, a rigid connection therebetween, of fulcrum stands spaced laterally from the first-mentioned stands, and rigid connections between the latter and the second-mentioned stands arranged in planes transverse to the plane of said first-mentioned rigid connection.

14. In a scale, the combination with a

complementary series of longitudinally spaced fulcrum stands, extension levers fulcrumed upon said stands, main levers, stands for the main levers arranged intermediate 40 said complementary series, rigid ties between the members of each longitudinal series, and rigid connections between the 45 members of said series and the fulcrum stands for the main levers.

15. In a scale, the combination with complementary main levers, of a lever adapted to be operated thereby, connections between 50 said operated lever and main levers including spaced loops having lateral projections extending adjacent each other, and means for detachably connecting said projections.

16. In a scale, the combination with a 55 pair of main levers, of a lever adapted to be operated thereby, connections between said main levers and operated lever comprising a bearing member having rigid depending loops, said member being detachably connected.

17. In a scale, the combination with main levers, of a lever adapted to be operated thereby, connections between said operated 60 lever and main levers including complementary bearing members, each of said members having a loop depending from one end thereof, and means for detachably connecting said bearing members.

In testimony whereof I affix my signature in presence of two witnesses.

JOHN H. A. BOUSFIELD.
